UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

CONNECTER SOCKET.

Application filed January 23, 1923. Serial No. 614,500.

My invention relates to electrical connecting devices and particularly to electric connector sockets.

The object of my invention is to provide 5 a relatively simple and inexpensive connector socket that shall be so constructed as to operatively engage with any one of the various types of contact plugs now in use.

In practicing my invention, I provide a 10 two-part electric-insulating casing in which is mounted a pair of resilient and initially flexed metal connector socket members. The socket members severally comprise an intermediate portion to which the end of a conductor wire is electrically connected, a plurality of forwardly-extending, resilient, spaced jaw members, and a rearwardly extending resilient holding member having a curved end portion to secure the socket member 15 in its proper operative position in the casing and to prevent its longitudinal motion relative thereto.

The inner one of the forwardly extending jaw members is substantially flat and is provided with a resilient tongue portion to interlock with and hold a flat connector-pin member, which the socket member may be caused to operatively engage. The other jaw member may be either of arcuate or of 20 V-shape in lateral section, or it may comprise a pair of spaced, resilient, flat, and parallel-extending portions located in a plane at right angles to the other jaw portions. Each of the metal socket members is held 25 in its initially flexed position within the casing by a three-point engagement therewith.

In the single sheet of drawings,

Figure 1 is a top plan view of one part 30 of an electric-insulating casing with the socket members embodying my invention, shown in normal position therein,

Fig. 2 is a top plan view of an electric insulating casing, with a portion thereof cut 35 away, to illustrate the position of the metal socket members when operatively engaging a pair of parallel-extending spaced flat connector pins,

Fig. 3 is a view similar to Fig. 2 but 40 illustrating the position of one of the metal socket members when engaging round contact pins spaced $5/8$ " apart,

Fig. 4 is a view similar to Fig. 2, but

illustrating the position of the metal socket members when operatively engaging round 55 contact pins spaced $3/4$ " apart,

Fig. 5 is a view similar to Fig. 2 but illustrating the position of the metal socket members when operatively engaging tandem 60 flat contact bars,

Fig. 6 is a view, in side elevation, of a part of the flat jaw portion of the metal socket member,

Fig. 7 is a top plan view of the portion 65 illustrated in Fig. 6,

Fig. 8 is a view, on a reduced scale, of the punched sheet plate constituting the metal socket member,

Fig. 9 is a view, in lateral section, through a metal socket member, taken on the line 70 IX-IX of Fig. 1, and

Figs. 10, 11 and 12 are views, in lateral section, of modified forms of socket members, the views corresponding to that of Fig. 9.

A connector socket 21 comprises two substantially similar casing-portions 22 and 23 which may be made of any suitable electric-insulating refractory material, and molded to the desired shape. In general, each of the members 22 and 23 is relatively flat and 80 is provided with a suitably recessed face on the inner side and a suitably curved surface on the outer side. The two members are secured together by a plurality of suitable bolts 24, co-operating with nuts, (not 85 shown) extending through openings 25 provided in each of the casing members 22 and 23. While a particular form of casing has been shown, the exact form and contour are not essential and form no part of my invention.

In the recessed inner face of the member 22 there are located a pair of resilient metal socket members 26, each comprising a single punched and formed piece of resilient and 90 relatively thin sheet metal, the contour of which before forming, is substantially as illustrated in Fig. 8 of the drawing.

An intermediate portion 27 of the sheet metal piece 26 comprises a rearwardly extending short strip which is folded upon itself in order to provide sufficient thickness of metal to receive a machine screw 28 which secures the end of a supply circuit lead 29 against the metal socket member 26 100 to electrically connect it thereto.

A forwardly-extending, resilient flat jaw portion 31 is bent upwardly at right angles to the plane of the intermediate portion 27 and a resilient tongue portion 32 is punched 5 therefrom and extends in a rearwardly direction thereof. The outer or free end of the tongue portion 32 is provided with an outwardly bent or projecting portion, which is adapted to operatively engage and interlock with an opening provided in the usual flat connector bar 33 now in extensive use in connector plugs. (See Fig. 2.) This interlocking of the tongue portion with the co-operating connector bar prevents accidental disengagement of the two parts during the operation thereof, thus making the interengagement of the connector socket and connector plug more effective and certain.

A second, forwardly-extending jaw portion 34 of the sheet metal piece 26, may be bent to any one of a variety of forms. For instance, as illustrated in Fig. 9 of the drawing, I may bend this jaw portion to substantially arcuate contour in lateral section. 25 I may also slot the portion 34, as illustrated in Fig. 12 of the drawing, for a purpose to be hereinafter set forth in detail. I may also so form the portion 34 as to be substantially of V-shape in lateral section, and 30 may slot the same, as illustrated in Fig. 11.

A rearwardly-extending resilient holding and locking portion 35 integral with the jaw portions and the intermediate portion, is bent upwardly at the same time that the jaw portion 34 is bent and is provided with a hook portion 36 which is adapted to fit around an upstanding lug or post 37 integral with the casing member 22. The outer end of the portion 35 is bent away from the 40 intermediate portion 27 of the metal socket member to such an extent that it is necessary to straighten the socket member structure when placing the same in its proper operative position within the recessed case of the 45 member 22.

This method provides an initially-flexed, resilient metal socket member that is held in the casing and against lateral movement relatively thereto by a three-point engagement therewith. These three points are the outer front-end of the jaw portion 34 which engages the outer wall of the recessed casing 50 22, the inner side wall of the intermediate portion 27, and the outer surface of the hook portion 36 of the spring member 35. It is understood, of course, that the width of the recess within which each of the metal socket members 35 are located, is relatively greater 55 than the width of the socket member and is such as to co-operate with the metal socket member to effect the mounting hereinbefore described.

The two conductor leads may be combined in the usual supply-circuit conductor 38 60 65 which extends outwardly through an open-

ing 39 in the inner end of the casing 21, a helical spring member 41 being provided to surround the supply-circuit conductor 38 for a short distance adjacent to the socket 21 to prevent undue kinking or bending thereof. 70 The helical spring 41 is provided with an enlarged inner end turn to hold the same in its proper operative position relatively to the casing 21.

The hereinbefore described connector 75 socket is intended to be used with any one of the connector plugs now in use, which have contact pins as follows:

1. Parallel flat bars spaced $\frac{1}{2}$ " between centers.
2. Round contact pins spaced $\frac{5}{8}$ " distance between centers.
3. Round contact pins spaced $\frac{3}{4}$ " between centers.
4. Tandem flat contact bars spaced $\frac{11}{16}$ " between centers.

When the device embodying my invention is employed with a connector plug having parallel flat bars, as per item 1 of the list above, the relative final positions of the 80 contact bars 33 and of the metal connector sockets 26 is substantially as illustrated in Fig. 2 of the drawing. The bars 33 operatively engage the adjacent inner faces of the 85 respective contact jaw portions 31, the projecting end of the tongue portion 32 fitting into the opening usually provided in the contact bars 33 adjacent the end thereof to interlock therewith.

During the operation of engaging the 100 metal socket members 26 with the contact bars 33, the outer free end of the jaw portions 31 of the respective members 26 are bent away from each other and then the intermediate portion of each of the metal 105 socket members 26 may move outwardly, (or away from each other) and cause a straightening of the socket member from the initially fixed position illustrated in Fig. 1 of the drawing to substantially the form and 110 position illustrated in Fig. 2 of the drawing. The extent of such lateral movement is, of course, entirely dependent upon the length of the contact bars 33 or to the extent to which these bars are forced into operative 115 engagement longitudinally of the socket members 26.

In Fig. 3 of the drawing, I have illustrated the position of the socket members 26 when they are operatively engaged by a pair of 120 round contact pins 42 spaced $\frac{5}{8}$ " distance between centers. When the outer ends of the contact pins 42 first operatively engage the metal socket members 26, engaging both contact jaw portions thereof, there will be a slight inward turning movement of the flat 125 jaw portions 31 and possibly of the entire forward end of each of the metal socket members around the intermediate point of engagement of each of the socket members 130

with the casing 22. There may also be a slight outward lateral movement of the intermediate portion of each of the socket members in the final stage of engagement, this outward movement being dependent upon the extent of the co-operating longitudinal engagement of the pins and socket members.

In Fig. 4, I have illustrated the final positions of the connector socket members 26 when operatively engaged by round contact pins 42, spaced $\frac{3}{4}$ " apart. In this case, there will be less turning movement of the outer ends of each of the flat jaw portions 31 and of the entire forward end of each of the socket members 26 toward each other during the initial period of engagement, and a greater outward lateral movement of the intermediate portion of the socket members in order to accommodate their positions to the substantially fixed positions and spacing of the contact pins, the action being substantially as described in the preceding paragraph. In either case of engagement with round contact pins, there is, of course, a resultant final straightening of the resilient socket members from their normal or inoperative flexed position, as illustrated in Fig. 1 of the drawing, to substantially the positions illustrated in Figs. 3 and 4 of the drawing.

It may also be noted that when the device embodying my invention is employed to operatively engage flat, spaced contact bars, as illustrated in Fig. 2 of the drawing, only the flat resilient jaw portions 31 are in operative engagement with the flat contact bars and the jaw portion 34 is effective only in co-operation with the integral spring extension 35 to insure close operative engagement between the jaw portion 31 and the contact bars 33. When the device embodying my invention is employed with round contact pins, as illustrated in Figs. 3 and 4 of the drawing, either both of the jaws 31 and 34 may operatively engage the pins 42 or it is possible that only the outer jaw portions 34 may operatively engage the contact pins 42, especially when the spacing between the round contact pins is relatively great, a position which is illustrated in Fig. 4 of the drawing.

Fig. 5 illustrates the position of the connector sockets 26 when employed with tandem flat connector bars 43 and while it is possible to employ substantially the same configuration of the jaw portion 34 as was heretofore employed in co-operation with the round pins or the parallel flat contact bars, I prefer to modify the shape of the jaw portions 34 in lateral section.

In Fig. 10, I have illustrated one modification comprising a slotted jaw portion, of substantially V-shape in lateral section, the flat bars 43 being adapted to fit between the

respective spaced parts of the jaw portion 34, as illustrated by the broken line section of Fig. 10.

I may also employ a slotted jaw portion 34 of arcuate form, as illustrated in Fig. 12 of the drawing. The contact bars 43 are located between the two parts of the jaw-portion 34 substantially as illustrated by the broken line section of Fig. 12.

Fig. 11 illustrates a still further modification in which the two parts of the resilient jaw portion 34 are bent to substantially parallel relation and are spaced a relatively small distance apart, determined by the thickness of the bars 43 which are adapted to fit between the integral parts 44 of the jaw portion 34. If the distance between centers of the tandem flat bars 43 is relatively small, they may operatively engage the jaw portion 31, as is illustrated in Fig. 5 of the drawing, or, if the distance between centers is relatively large, they may engage only the parts of the jaw portion 34, as illustrated for instance, in Fig. 11 of the drawing. The device embodying my invention thus provides what may be termed a "universal" connector socket that is effective to co-operate with any one of a plurality of different connector plugs of the type hereinbefore enumerated and is effective to make close operative engagement with the co-operating connector plug pins, thereby insuring that there will be no overheating of the connector plug or socket.

The co-operating connector socket and plug members may be easily and quickly brought into proper operative engagement and may be also easily and quickly disengaged, insuring that there will be practically no destructive arcing between the co-operating contact surfaces either when engaging the two parts or when disengaging the same.

The metal socket member 26 is of substantially the contour illustrated in Fig. 8 of the drawing, and may be punched from a relatively thin sheet metal member and subsequently bent to the desired form. The rearward extension 35 may be so bent as to necessitate flexing the same when placing the socket member in proper operative position in the recessed inner surface, of the molded member 22. As the metal socket members are merely laid in the grooves, the assembly of such a device can be accomplished easily and rapidly. Each of the resilient socket members will have slight lateral movement of either the front or outer end portion, or of the intermediate portion, depending entirely upon the spacing of the contact pins engaging the socket members, thereby insuring close operative engagement between the co-operating connector parts, while still permitting of easily and quickly inserting or removing the sockets and pins.

Various modifications and changes may

be made in the device embodying my invention without departing from the spirit and scope thereof, and I desire, therefore, that only such limitations shall be placed thereon as are imposed by the prior art or set forth in the appended claims.

I claim as my invention:

1. In a connector socket, in combination, a casing, and a formed resilient, single-piece socket member located in said casing comprising integral flexed means for resiliently positioning said socket member in the casing, a plurality of integral jaw portions adjacent said flexed means, and integral means intermediate said flexed means and said jaw portions for securing an electric supply conductor to said socket member.

2. In a connector socket, in combination, a casing, and a single-piece socket member located in said casing comprising a plurality of spaced-apart, parallel, jaw-portions, a flexed portion for resiliently holding said socket member in said casing, and an intermediate portion adapted to have an electric supply conductor connected thereto.

3. In a connector socket, in combination, a casing and single-piece socket member located in said casing comprising a pair of forwardly-extending, parallel, spaced resilient jaw portions, one of said jaw portions being operative to engage a flat contact pin and the pair of jaw portions being operative to engage a round contact pin, a rearwardly-extending, resilient holding portion for positively securing said socket member in the casing, and an intermediate portion adapted for connection to an electric supply conductor.

4. In a connector socket, in combination, a casing, and a socket member mounted in said casing and movable laterally relatively thereto and formed from a single piece of sheet metal and comprising an intermediate portion, a forwardly-extending portion of substantially arcuate shape in cross-section, a forwardly-extending, resilient, flat tongue portion, substantially parallel to and spaced apart from said portion of arcuate section and a rearwardly-extending, resilient portion having integral means for preventing longitudinal movement of said socket member in said casing.

5. In a connector socket, in combination, a casing and a pair of resilient single-piece socket members disposed in said casing, each socket member comprising means for resiliently securing said member in said casing, a plurality of parallel, forwardly-extending,

spaced, resilient jaw portions, one of said jaw portions being flat and adapted to operatively engage a flat contact pin, and resilient means on said flat jaw-portion for interlocking with, and holding a flat contact pin in positive engagement with, said socket member.

6. In a connector socket, in combination, a casing and a pair of single-piece metal socket members each comprising a plurality of forwardly extending resilient jaw portions, and a curved, rearwardly-extending, resilient hook portion for holding said socket member longitudinally of said casing while permitting a lateral movement of the forwardly extending jaw portions of said socket member when engaging various pairs of contact pins.

7. In a connector socket, in combination, a casing and a pair of single-piece, resilient, metal socket members located therein, each of said socket members comprising a plurality of spaced, resilient, contact-jaw portions, one of said jaw portions being effective to operatively engage one of a pair of spaced, parallel, flat contact pins, independently of the remaining jaw portions, and the remaining jaw portions being effective to operatively engage one of a pair of spaced, round, or tandem flat contact pins.

8. In a connector socket, in combination, a casing having integral upstanding lugs therein, and a pair of single-piece flexed, resilient, metal socket members located therein comprising a plurality of forwardly-extending resilient jaw portions, a rearwardly extending portion having a hook portion at the end thereof for engaging said lugs, and means for connecting a conductor to said socket member intermediate its ends.

9. In a connector socket, in combination, a casing, having a plurality of recesses extending longitudinally thereof located therein, the lateral space between the walls of said recesses being substantially greater than the width of the socket members, and a pair of single-piece socket members located in said recesses comprising integral means for resiliently supporting said socket members in said recesses whereby lateral movement of the socket members may be effected to accommodate their positions to pairs of contact pins having different distances therebetween.

In testimony whereof, I have hereunto subscribed my name this 22nd day of January, 1923.

ORA A. COLBY.
